UNITED STATES PATENT OFFICE.

WILLIAM F. LAUTENSCHLAGER, OF CINCINNATI, OHIO.

REMOVABLE JACKET FOR SPARK-PLUG ELECTRODES.

Application filed August 8, 1921 Serial No. 490,668.

To all whom it may concern:

Be it known that I, WILLIAM F. LAUTENSCHLAGER, a citizen of the United States, residing at Cincinnati, in the county of Hamilton and State of Ohio, have invented certain new and useful Improvements in Removable Jackets for Spark-Plug Electrodes, of which the following is a specification.

My invention relates to jackets adapted to be placed over the electrodes of spark plugs, whereby the said electrodes are prevented from being burnt away.

Heretofore, electrodes of spark plugs have been burnt away by the heat of the spark. The continued passage of the spark heats these electrodes to a high temperature as they do not possess sufficient radiating surface. The electrodes therefore retain their heat and in a short time become red hot. In this condition a high tension electric spark rapidly burns away the metal, whereby the life of a spark plug is greatly decreased.

It is the object of my invention to increase the life of the spark plugs; further, to provide jackets adapted to be placed about the electrodes of spark plugs whereby the same are prevented from being worn away and the life of the spark plug increased; further, to provide increased radiating surfaces for the electrodes whereby the same are kept in a comparatively cool condition; further, to so construct the jackets to be capable of rotation and present new spark surfaces, whereby the proper length of the spark gap is maintained; further, to provide a means of holding the jackets on the electrodes; further, to provide a ready and convenient means of placing the jackets on the electrodes; and further, to provide a means whereby the jackets may be readily and cheaply manufactured.

My invention consists in the provision of a jacket adapted to be placed about the electrodes of a spark plug; further, in the construction of the jacket by forming the same of coiled wire; further, in means whereby increased radiating surface is obtained; further, in means whereby the jackets are held on the electrodes; further, in means whereby new spark surfaces may be presented in order to maintain a spark gap of proper length; further, in means whereby a number of jackets may be formed in a continuous length when manufactured; further, in means to enable the jackets to be

placed on the electrodes and afterwards readily broken off of such continuous length of jackets.

My invention further consists in the parts, combination and arrangement of parts, and in the details of construction, as herein set forth and claimed.

In the drawing:

Fig. 1 is a perspective view of my improved device;

Fig. 2 is a central vertical section of the upper end of an internal combustion engine having a spark plug therein, to which my improved device is applied;

Fig. 3 is a bottom view of a spark plug having my improved device thereon;

Fig. 4 is a central vertical section of the same taken on the line 4—4 of Fig. 3;

Fig. 5 is a central vertical section of the device shown in Fig. 3 partly broken away and taken in a plane similar to that of Fig. 4 but showing the parts very much enlarged;

Fig. 6 is a side elevation of a number of the jackets sufficient to equip the spark plugs of a six cylinder engine, shown integral in one length preparatory to being applied; and

Fig. 7 is a perspective view, showing the manner in which my improved device is applied to the electrodes of a spark plug.

In the embodiment of my invention as illustrated, a cylinder 10 of an internal combustion engine 11 has therein a spark plug 12, comprising an outer shell 13 and an inner electrode 14 insulated from the outer shell by an insulating tube 15. A spark electrode 16 is secured to the outer jacket 13 adapted to coact with the inner electrode 14 to form a spark gap 17. The upper end of the inner electrode may be connected by suitable cables to ignition devices not here shown, because well understood. The outer jacket 13 forms one terminal of a high tension circuit, and the inner electrode 14 forms the other terminal of the high tension circuit. When the ignition devices are actuated, an electric current of high potential is set up in the circuit and bridges the spark gap 17, whereby a high tension spark is formed therein and the gases in the engine cylinder fired.

In order that the electrodes will not be subject to the deteriorating effect of the spark discharge, jackets 18 are adapted to be placed thereabout. These jackets comprise helical coils of wire 19, having ventilating spaces 20 therebetween. The inter-

nal diameter of the coils are preferably slightly smaller than the diameter of the electrodes, so that when the jackets are placed thereon, they will be held in place by 5 spring tension.

I prefer to form the coils when manufactured in one continuous length, and then cut the same into such lengths containing such numbers of jackets as will correspond 10 to the number of cylinders in the engines, the spark plug in each cylinder requiring two jackets. (See Fig. 6.) For instance, for a four cylinder engine the jackets are integrally formed in lengths numbering 15 eight jackets, and for six cylinder engines a length contained twelve jackets, and so on. At points where the several jackets are joined, I prefer to score the same, for instance, by a thin emery wheel, as shown at 20 21. This scoring cuts part of the metal of the coils away at this particular point which readily permits the jackets to be afterwards severed from the main length.

In placing the jackets on the electrodes 25 the length of the jackets is held in the hand and the end jacket screwed on in the direction of the lead of the helical coils. It will be observed that the coils of the spring grip the electrodes tightly for the reason that 30 their internal diameters are slightly smaller than the diameters of the electrodes, the coils acting frictionally as a screw.

When the jackets have once been put in 35 place, they are not easily removed unless done so forcibly with a pair of pliers, the spring action of the coils tending to wind themselves tightly about the electrodes. After the entire jacket is in place, the main length is bent at an angle thereto which 40 breaks the wire at a point where the coils have been scored, thus severing the jacket from the main length.

In use the spark will pass from the coils of the jacket on one of the electrodes, to 45 the coils of the jacket on the other of the electrodes. The electrodes themselves will not be subject to wear or injury in any manner as the spark passes only between the coils of the jackets. The spring tension of 50 the jackets make perfect electrical contact with the electrodes and therefore act electrically as a part thereof. The temperature of the jackets is kept at a low heat generated by the spark point by the incoming charge 55 of gases, which circulate perfectly around

the coils 19 through the spaces 20, preventing scaling thereof and the consequent wearing away of the metal.

After a period of use, however, portions of the coil will become slightly worn away or corroded whereupon it is only necessary to turn the jackets slightly in the direction of the lead of the coils, so as to present new surfaces between which the spark may pass. This may be repeated at intervals, until the 60 coils of the jackets become worn, after which new jackets may be slipped over the electrodes. In this manner the electrodes of the spark plug become practically indestructible and the life of the spark plug is thereby prolonged indefinitely. In no case where my improved device is employed, is it necessary to discard a spark plug because of worn electrodes.

I do not limit myself to the particular construction, as herein shown, but can employ a cylindrical body capable of exerting sufficient spring tension on the electrodes to hold it in place. It is further possible to employ wire of square or rectangular cross section in forming the coils. Any other form of jackets may be employed capable of being slipped over the electrodes without departing in any manner from the spirit of my invention within the scope of the appended claims.

What I claim as new and desire to secure by Letters Patent is:

1. In a spark plug, a pair of electrodes having free ends and disposed at an angle to each other, a coiled spring member frictionally held on the free end of each electrode adapted to form a spark gap and said coiled spring members having an inside diameter slightly less than the outside 90 diameter of said electrodes, substantially as described.

2. In a spark plug, a pair of electrodes having free ends and at right angles to each other, coiled wire spring members having an inside diameter slightly less than said electrodes and frictionally held on said ends, respectively, and spaced apart from each other whereby a spark gap is formed and said spring members are adapted to be conveniently removed from and placed on said electrodes, substantially as described and for the purposes specified.

WILLIAM F. LAUTENSCHLAGER.
